UNITED STATES PATENT OFFICE.

BERTHA STRASBURGER, OF NEW YORK, N. Y.

DESIGN FOR A LAMP OR CANDLE SHADE.

SPECIFICATION forming part of Design No. 36,002, dated August 12, 1902.

Application filed June 26, 1902. Serial No. 113,381. Term of patent 3½ years.

To all whom it may concern:

Be it known that I, BERTHA STRASBURGER, a citizen of the United States, residing at New York, in the county of New York and State 5 of New York, have invented and produced a new, original, and ornamental Design for Lamp or Candle Shades; and I do hereby declare the following to be a full, clear, and exact description of the same, reference being 10 had to the accompanying drawings, forming a part thereof.

My invention relates to a design for lamp or candle shades; and it consists of the configuration shown in the accompanying drawings, 15 in which—

As shown in the drawings, the leading or material feature of my design consists of the 20 assemblage in the form of a lamp or candle shade of ribbon loops and streamers and flowers arranged or disposed as follows:

As shown in Fig. 1, a series of loops A and flowers B surmount the top of the shade and are encircled by a ribbon C. Pendent from 25 near the top of the shade, beneath the loops A, are series of streamers D and E of different lengths and carrying flowers F at their ends. Also pendent from beneath loops A is a series of streamers G, carrying bows H and 30 flowers I at their ends, the said flowers F and I and bows H producing a full or cluster effect about the base of the shade.

Having described my invention, what I claim as new, and desire to secure by Letters 35 Patent, is—

The ornamental design for a lamp or candle shade, as herein shown and described.

In testimony whereof I affix my signature in presence of two witnesses.

BERTHA STRASBURGER.
